DESIGN FOR A TEA WAGON OR SIMILAR ARTICLE

Halbert Creston Doner, Toledo, Ohio, assignor to Libbey-Owens-Ford Glass Company, Toledo, Ohio

Application September 27, 1943, Serial No. 111,216

Term of patent 14 years

(Cl. D33—13)

To all whom it may concern:

Be it known that I, Halbert Creston Doner, a citizen of the United States, residing at Toledo, in the county of Lucas and State of Ohio, have invented a new, original, and ornamental Design for a Tea Wagon or Similar Article, of which the following is a specification, reference being had to the accompanying drawing, forming part thereof.

Fig. 1 is a front perspective view of a tea wagon, showing my new design, with the upper compartment open; and

Fig. 2 is a similar perspective view on a reduced scale, with the upper compartment closed.

The rear of the tea wagon is plain and unornamented and the side not illustrated is substantially the same as the side illustrated. Base supports as shown in the front of the tea wagon also appear in the rear.

I claim:

The ornamental design for a tea wagon or similar article, substantially as shown and described.

HALBERT CRESTON DONER.
